CLAIM

The ornamental design for a camera mount, as shown and described.

DESCRIPTION

FIG. 1 is an upper, front, right perspective view of an embodiment of a camera mount.

FIG. 2 is a lower, front, left perspective view of the camera mount shown in FIG. 1.

FIG. 3 is a top plan view of the camera mount shown in FIG. 1.

FIG. 4 is a rear elevation view of the camera mount shown in FIG. 1.

FIG. 5 is a front elevation view of the camera mount shown in FIG. 1.

FIG. 6 is a right elevation view of the camera mount shown in FIG. 1.

FIG. 7 is a left elevation view of the camera mount shown in FIG. 1.

FIG. 8 is an upper, front, right perspective view of another embodiment of a camera mount.

FIG. 9 is a lower, front, left perspective view of the camera mount shown in FIG. 8.

FIG. 10 is a top plan view of the camera mount shown in FIG. 8.

FIG. 11 is a rear elevation view of the camera mount shown in FIG. 8.

FIG. 12 is a front elevation view of the camera mount shown in FIG. 8.

FIG. 13 is a right elevation view of the camera mount shown in FIG. 8.

FIG. 14 is a left elevation view of the camera mount shown in FIG. 8.

FIG. 15 is an upper, front, right perspective view of another embodiment of another embodiment of a camera mount

FIG. 16 is a lower, front, left perspective view of the camera mount shown in FIG. 15.

FIG. 17 is a top plan view of the camera mount shown in FIG. 15.

FIG. 18 is a rear elevation view of the camera mount shown in FIG. 15.

FIG. 19 is a front elevation view of the camera mount shown in FIG. 15.

(Continued)

FIG. 20 is a right elevation view of the camera mount shown in FIG. 15.
 FIG. 21 is a left elevation view of the camera mount shown in FIG. 15.
 FIG. 22 is an upper, front, right perspective view of another embodiment of a camera mount.
 FIG. 23 is a lower, front, left perspective view of the camera mount shown in FIG. 22.
 FIG. 24 is a top plan view of the camera mount shown in FIG. 22.
 FIG. 25 is a rear elevation view of the camera mount shown in FIG. 22.
 FIG. 26 is a front elevation view of the camera mount shown in FIG. 22.
 FIG. 27 is a right elevation view of the camera mount shown in FIG. 22; and,
 FIG. 28 is a left elevation view of the camera mount shown in FIG. 22.
